UNITED STATES PATENT OFFICE.

JAMES A. SPENCER, OF NEW YORK, N. Y.

METHOD OF AND MEANS FOR RECLAIMING PRINTED TAPES, ETC

Application filed April 15, 1926. Serial No. 102,284.

The object of my invention is to clean or wash the ink from printed tapes or strips to permit the re-use thereof. My invention is particularly applicable to cleaning printed characters, ink etc. from tape or strips of suitable material commonly used in connection with stock, bond and news tickers. My invention is especially adapted to remove the printed ink characters, etc., from translucent strips or tapes upon which stock, bond and news items are printed and thereafter projected on a screen for observation of the printed matter on an enlarged scale, such as is used in the New York Stock Exchange. 10 brokers' offices and in analogous relations, whereby stock and bond quotations and news may be observed from a distance by a number of people simultaneously.

My invention may be used for cleaning or 20 washing the printed characters, ink, etc. from tapes or strips after the same have passed from the stock ticker and through a projecting machine in such a way that the tape or strip will be reclaimed, cleaned and 25 rolled up ready for re-use as rapidly as it is released from the ticker, or my improvement may be used for cleaning the tape or strip at any time after the same has been printed in the ticker without passing directly therefrom to my improved tape cleaning devices.

In the particular embodiment of my invention as illustrated in the accompanying drawings, the tape after it is printed and passes from a stock or news ticker, travels 35 through a projection machine or apparatus from which the printed matter is projected or reflected on a screen, and the tape passes thence through a bath of a non-inflammable cleaning solution for dissolving the ink, whence the washed tape or strip passes 40 through devices to remove therefrom any residue cleaning solution that may adhere to the tape, the cleaned tape preferably passing to a take-up spool upon which the washed 45 or reclaimed tape is wound for further use. My invention comprises means for passing the printed tape or strip through the cleaning solution and winding it upon a take-up spool substantially in accordance with the 50 feeding of the tape from the ticker, the operation of the take-up spool being controlled by the feeding of the tape in such a way that when the ticker stops feeding the tape the take-up spool will automatically stop operation 55 at a proper time and, in case the take-up spool should tend to wind up the tape faster

than it is fed from the solution, the spool will be caused to stop operation at an appropriate time so as not to pull the tape unduly with respect to its feeding means. 60

My invention also comprises novel details of improvement that will be more fully hereinafter set forth and then pointed out in the claims.

Reference is to be had to the accompanying drawings forming a part hereof, wherein

Fig. 1 is a side elevation illustrating my invention as applied in connection with a stock or news ticker;

Fig. 2 is an enlarged side view, partly broken, of parts shown in Fig. 1;

Fig. 3 is an edge view, partly in section, looking from the left hand side of Fig. 2;

Fig. 3^a is a sectional detail of the take-up 75 spool;

Fig. 4 is a detail view looking from the left hand side of Fig. 3, illustrating parts detached;

Fig. 5 is a vertical section through Fig. 3;

Figs. 6 and 7 are enlarged detail views 80 illustrating controlling devices for the reclaiming means in different positions of operation; and

Fig. 8 is a diagrammatic illustration of the 85 tape cleaning devices.

Similar numerals of reference indicate corresponding parts in the several views.

At 1 is indicated a stock or news ticker of any suitable or well known construction of the variety provided with a printing wheel 2 for printing stock quotations, news matter, etc. upon a tape or strip A. The tape A may be supplied to the ticker from a reel A² in any usual way. At 3 is indicated, in a generally diagrammatic manner, a so-called projecting apparatus through which the printed tape from the ticker passes, and which is adapted to project the printed matter from the tape upon a screen or other object B for observation of the printing as 90 on an enlarged scale. For such purpose the tape A may be translucent. A stock quotation projection machine suitable for the purpose is set forth in Letters Patent to Ashbel Green, No. 1,523,767, granted January 20, 1925. At 4 is indicated, generally 95 my improved apparatus for reclaiming the tape or strip A as by washing the printed matter from the same during its travel. At 5 is a tank, shown open on the top, 100 adapted to contain a suitable cleaning solution or fluid for the printing ink on the

tape, preferably a non-inflammable solution which will not injure the tape but will dissolve or loosen the ink thereon. The tape A is fed through the solution in the tank 5 and is shown passing over an upper edge of the tank and between a pair of pads or rubbers 6, 7 maintained in the tank below the level of the solution, (Figs. 3 and 5). The pads or rubbers may be of felt and are 10 adapted to rub or brush the dissolved or loosened ink from the surface of the tape. The lower pad 6 is stationary and the upper rubber or pad 7 is movable toward and from the lower rubber or pad to admit the tape 15 therebetween, and is shown resiliently pressed toward rubber or pad 6 to correspondingly bear upon the printed side of the tape passing between the rubbers or pads. The frame of the apparatus is preferably made in 20 two sections 8 and 9 detachably connected together for convenience in threading the tape between the rubbers or pads and various buffers or rollers to be described. While the lower pad 6 may be supported in any 25 suitable way I have shown the same supported upon the removable section 9 of the main frame, which section is shown provided with a cross bar 10 upon which the pad 6 is secured. The rubber or pad 7 30 is secured to a block 11 to which a rod 12 is attached, which rod is slidably guided in a bore in a cross bar 13 secured between the side plates of the frame section 9. Said rod carries a stop or collar 14 against which a 35 coil spring 15 on the rod bears, said spring also bearing against the cross bar 13, (Fig. 5), whereby the rubber or pad 7 is resiliently pressed toward pad 6. The lower end of the section 9 with the rubbers or pads 6, 40 7 is located within the bath of solution or fluid in tank 5, whereby when the tape is pulled through the bath in contact with the rubbers or pads the type on the tape, which has been dissolved or loosened by the solution, will be more or less removed from the tape. The section 9 may be detachably connected with section 8 of the main frame by means of hooks 16 on section 9 adapted 45 to engage notches or the like 17 in the adjacent vertical edges of the frame section 8, (Figs. 2 and 4), whereby the section 9 is hung from the section 8 with the edges of the sections abutting, and the section 9 is shown provided with pivotally supported 50 latches 18 having recesses 19 adapted to engage stops or screws 20 on section 8. By moving back the latches from the stops the section 9 may be detached from section 8 of the frame. 55 A pair of buffers, rubbers or rollers at 21, 22 are so located that the tape A will pass between them, which rubbers or buffers are more or less within the tank 5 and are subject to the solution therein, so 60 as to rotate against the tape with a rubbing or wiping action while it is wet from the solution. The rubbers or buffers 21 may comprise felt or other suitable relatively soft material to act in the nature of brushes. The shaft 23 of buffer 21 is journaled upon 70 the frame section 9 and the shaft 24 of buffer 22 is journaled upon the frame section 8. Another pair of rubbers, buffers or rollers 25 and 26 receive the tape between them and are located above the bath so as to 75 serve for drying the tape by rubbing or brushing against the same. The shaft 27 of rubber or buffer 25 is journaled upon frame section 9, and the shaft 28 of rubber or buffer 26 is journaled upon frame 80 section 8. Above the rubbers or buffers 25 and 26 are feed rollers 29 and 30 for the tape. The shaft 31 of roller 29 is journaled upon the frame section 8 and the shaft or spindle 32 of roller 30 is carried 85 by the forked portion 33^a of an arm 33 that is pivoted upon a pin or shaft 34 carried by an extension 8^a of frame section 8, (Figs. 1 and 4). The outer or free end of arm 33 is connected with a spring 35 attached to 90 an adjusting screw 36 that is slidable in a bore in a bar 37 secured to the extension 8^a, a nut 38 on the screw operating against the bar 37 serving to adjust the screw lengthwise and retain it in set position for 95 varying the tension of spring 35 with respect to arm 33, whereby the pressure of roller 30 against roller 29 may be adjusted for feeding the tape which passes between said rollers. The periphery of roller 29 is preferably grooved to guide the tape, and the surface of roller 30 is such as to fit between the flanges of roller 29 in engagement 100 with the tape, (Figs. 3 and 5). 105 Any suitable gearing or means may be provided for rotating the various buffers and rollers. I have illustrated a worm wheel 39 that is secured on shaft 31 of roll 29 and in mesh with a driving worm 40 upon a shaft 41 journaled in bearings upon frame 110 section 8, which shaft is driven by a suitable electric motor 42, whereby the feed roll 29 will rotate in the direction of the arrow a in Fig. 5 for feeding the cleaned tape from the tank, (Fig. 5). The shaft 31 is provided with a gear 43, (shown on the side of frame section 8 opposite worm wheel 39), which gear is in mesh with a pinion or gear 44 secured upon the upper end of a vertically disposed shaft 45 journaled in bearings 46 on the adjacent side of frame section 8, (Figs. 3 and 4). The shaft 45 is provided with a bevel gear 47 in mesh with a corresponding gear 48 on shaft 28, and shaft 45 is provided with another gear 49 115 in mesh with a bevel gear 50 on shaft 24. The shaft 28 is provided with a gear 51 adapted to mesh with a gear 52 secured on shaft 27, whereby the buffers 25 and 26 will be rotated in opposite directions against the 120 125 130

direction of feed of tape A by the rollers 29 and 30, as indicated by the arrows *b* and *c* in Fig. 5. The shaft 24 is provided with a gear 53 adapted to mesh with a gear 54 secured on shaft 23, whereby the buffers 21 and 22 will be driven in opposite directions against the direction of feed of tape A, as indicated by the arrows *d* and *e* in Fig. 5.

The gearing described is such that when the motor is operating the tape will be fed or pulled through the solution after being released from the ticker at a speed approximating the speed at which the tape is delivered from the ticker. During such feed of the tape by the rollers 29 and 30 the rotation of the buffers or rollers 21, 22 and 25, 26 in engagement with the tape will serve to clear all dissolved ink from the tape and deliver the tape from the apparatus in a substantially dry condition. The pairs of buffers 21, 22 and 25, 26 are shown staggered, respectively, in such a manner as to force the tape against them with the surface of the tape upon which the printing was produced against the surface of the buffers 21 and 25. Since the gears 52 and 54 are on the shafts 27 and 23 that are carried by the frame section 8 said gears will be unmeshed from the corresponding gears 51 and 53 when said section is removed from section 8 and will be correspondingly intermeshed when section 9 is replaced against section 8. The removability of section 9 from section 8 of the main frame permits ready location of the tape between the brushing or buffing rollers when a tape is to be cleaned from printing, and the rocking of arm 33 permits the tape to be inserted between the rolls 29 and 30 when a new tape is applied in a machine.

At 55 is a take-up spool for the cleaned tape, the shaft 56 of which spool is journaled upon an arm 8^a of frame section 8, (Fig. 1). The spool may be detachably connected with shaft 56 in any well known way, and such spool is of the grooved variety. I have shown shaft 56 provided with pin 57 adapted to receive a notch 58 in the hub of spool 55 to rotate it, and a nut 59 on the end of the shaft is adapted to bear against the outer side of the spool to detachably retain the spool on the shaft, (Fig. 3^a). The shaft 56 is shown provided with a pulley 60 receiving a belt 61 from a pulley 62 secured on shaft 31, whereby when said shaft is rotated the spool will be correspondingly rotated to wind up the cleaned tape. The belt may be so adjusted as to slip as required when the tape is being wound up to allow for increasing diameter of the re-wound tape, and not to pull the tape too fast respecting its feed from the rollers 29 and 30.

Since the winding or take-up of the cleaned tape upon spool 55 will not be in

exact accord with the feeding of the tape by the ticker, the latter being fed more or less intermittently as the printing occurs, with stoppage as customary in tickers, I provide means to automatically control the operation of motor 42, hence the operation of the feed rolls, the buffers and the take-up spool 55. I utilize slack in the tape between the ticker and the bath for controlling the operation of motor 42. In the circuit of the motor I provide spring contacts 63 and 64 shown respectively connected to the conductors 65 and 66 of the motor circuit, which spring contacts are carried by suitable insulation at 67 arranged to make and break the circuit of the motor according to the amount of slack in tape A, preferably adjacent to the tank 5. The contact spring 64 is adapted to be controlled by a rotative member 68, which is preferably of insulation and secured upon a shaft 69 that is journaled in a bracket 70 secured upon the insulation 67. The member 68 is shown in the form of a disk provided with a notch 68^a having an edge portion 68^b adapted to engage the adjacent curved edge 64^a of contact spring 64, (Figs. 6 and 7). The member 68 is shown clamped between disks 71 secured upon shaft 69, (Fig. 3). Said shaft is shown provided with an outwardly projecting arm 69^a normally drawn down by a spring 72 shown connected with said shaft and with the base 73, tending to so rotate the member 68 as to move its edge 68^b upwardly to permit closing of the circuit at 106 the contact springs 63, 64, (Fig. 6). The arm 69^a is provided with a lateral projection 69^b located against the tape A and within the bight or loop A' of the latter, shown adjacent to tank 5 and without the latter. 105 When the motor is idle and the ticker feeds the tape A with sufficient speed to permit the bight or slack A' to form relatively deep in the tape, the bight hanging between the projector 3 and the adjacent edge of 110 tape 5, (Fig. 6), the projection 69^b will descend in the bight causing such rotation of member 68 as will properly move edge 68^b and permit spring contact 64 to rise and close the motor circuit at contact 63, whereupon the motor will start rotating and will cause operation of the feed rolls 29 and 30 to pull the tape through the solution in the bath, and at the same time will cause operation of the buffing or brushing rolls 21, 22 115 and 25, 26 for cleaning the tape, simultaneously causing operation of the take-up spool 55 for winding up the tape fed by the rolls 29 and 30. If the feeding of the tape through the solution is faster than the feeding of the tape by the ticker the bight A' in the tape will gradually become relatively shallow or reduced in extent and the projection 69^b will be correspondingly raised 120 to advance the edge 68^b of member 68 to en-

gage the contact spring 64 to break the motor circuit at 63, 64 and temporarily stop the motor and the feeding and winding of the tape until the ticker has fed sufficient 5 tape to permit lowering of the projection 69^b in the bight A' to again rock the member 68 sufficiently to permit closing of the motor circuit at 63, 64 to again start the motor for further feeding and winding up of the tape, 10 and so on.

It will be understood from the foregoing that the ticker may print and feed the tape as may be required in the ticker service. The tape will pass through the projector for 15 projecting the printed matter upon the screen, and the type printed upon the ticker will be cleaned therefrom and the tape wound on the spool 55 for re-use, all in a consecutive manner. Great saving may be 20 effected by means of my invention in that the re-use of the translucent or analogous tape from which the printed characters have been removed overcomes the necessity heretofore experienced of using a new tape in a ticker 25 each time the printing of a tape is required.

While I have referred to printing information upon tape or strips, as in a stock and news ticker, and cleaning the ink therefrom, during progress of the tape through a cleaning 30 solution or compound, it will be understood that my invention, in its broad aspects, is adapted to clean other material from the surfaces of tapes or strips by means of a suitable solution or the like that will dissolve 35 such material during the passage of the tape for reclaiming the tapes or the like for re-use. Furthermore, my invention is not limited to the details of construction and arrangement of parts set forth, since the 40 same may be varied, within the scope of the appended claims, without departing from the spirit of my invention.

By the term "solution" I mean any 45 suitable substance which will serve to dissolve material on the surface of the tape without injuring the latter, and by the term "tape" I mean a strip of suitable material upon the surface of which information may 50 be applied, as in the nature of ticker tape, translucent tape or strips, such as Trans Lux Celophane, and the like.

Having now described my invention what I claim is:

1. Mechanism of the class described comprising means to apply material to the surface of tape and feed the tape therefrom, a 55 cleaning solution, and devices to guide and feed the tape through the solution as fed from the first named means after said material has been applied on the tape.

2. Mechanism as set forth in claim 1, including means controlled by the progress of the tape for feeding the tape through the solution in substantial accord with the feeding 60 of the tape from the first named means.

3. Mechanism of the class described comprising means to apply material to the surface of tape and feed the tape therefrom, a cleaning solution, means to guide the tape to the solution as fed from the first named 70 means, devices within the solution to engage the tape and remove dissolved material therefrom, and means to feed the reclaimed tape from the solution.

4. Mechanism as set forth in claim 3, including means controlled by the progress of the tape for feeding the tape through the solution in substantial accord with the feeding of the tape from the first named 75 means.

5. The combination of means to apply information upon tape and feed the tape therefrom, means to maintain a solution for dissolving the printed matter from the tape, means to guide the tape to the solution as 80 fed from the said means, devices to remove the dissolved material from the tape, and means to feed the tape from the solution.

6. The combination of means to apply information upon tape as set forth in claim 85 5, in which the devices for removing the printed matter from the tape include a rubber within the solution to engage the printed surface of the tape, means resiliently pressing the rubber against the tape, and means 90 to feed the tape through the solution.

7. The combination of means to apply information upon tape as set forth in claim 5, in which the devices for removing the printed matter from the tape include a rubber within the solution to engage the printed surface of the tape, a rod connected to said rubber, guiding means for the rod, a spring 100 cooperating with the rod to force the rubber resiliently against the printed surface of 105 the tape, and means to feed the reclaimed tape from the solution.

8. The combination of means to apply information upon tape and feed the printed tape, means to maintain a solution 110 for dissolving the printed matter from the tape, devices to remove the dissolved material from the tape, means to feed the tape from the solution, rubbing means within the solution to remove dissolved printed matter 115 from the tape, rotary rubbing means to engage the rubbed tape, and feed rolls for the tape beyond the rubbing means and means controlled by the tape between the applying means and the solution to control said last named feeding and rubbing means.

9. The combination of means to apply information upon tape as set forth in claim 8, comprising a take-up spool for the tape, and means to rotate said spool in substantial accord with the feeding of the tape from the applying means.

10. Mechanism for reclaiming printed tape comprising means to apply information upon the tape and feed the tape therefrom, 130

means to guide the tape through a cleaning solution, a take-up spool for the reclaimed tape, a motor and devices operative thereby to rotate the spool, a circuit for the motor, 5 including make and break contacts, and means to actuate one of the contacts, said means being cooperative with the tape to make and break the motor circuit in accordance with the progress of the tape as fed 10 from the applying means.

11. Mechanism for reclaiming printed tape as set forth in claim 10, in which the means to control the contacts includes a projection in engagement with the tape for 15 opening and closing the motor circuit in accordance with the feed of the tape from the applying means.

12. Mechanism for reclaiming printed tape as set forth in claim 10, in which the means to control the contacts include a projection in engagement with a bight in the tape between the applying means and the cleaning solution for closing the motor circuit to cause operation of the take-up spool 25 when the bight of the tape is relatively deep as fed from the applying means and for breaking the motor circuit when the bight in the tape is relatively shallow.

13. Mechanism for reclaiming printed tape comprising means to apply information upon the tape and feed the tape therefrom, means to guide the tape through a cleaning solution, a take-up spool for the reclaimed tape, a motor and devices operative thereby to rotate the spool, a circuit for the motor including make and break contacts, means to actuate one of the contacts to make and break the motor circuit, said means including an insulating member 35 provided with a projecting portion to engage said contact, and a shaft rotatively supporting said member, said shaft being provided with an arm having a projection to engage a bight in the tape for causing 40 closing of the circuit of said contacts when the bight is relatively deep as fed from the applying means and for actuating the said contact to break the motor circuit when the bight is relatively shallow to stop rotation of the spool and check winding up of 45 the reclaimed tape.

14. Mechanism for reclaiming tape having dissolvable material on its surface comprising a tank for a dissolving solution, 50 rubbing devices for the dissolved material on the tape, means to feed the tape through

the solution, driving devices for the feeding means, and means cooperative with the tape to control the operation of the driving devices in correspondence with the feeding 60 of the tape.

15. Mechanism for reclaiming tape as set forth in claim 14, including a tape-up spool for the tape, and means actuated by the driving devices for operating the spool to 65 wind up the tape as fed by the tape feeding means.

16. Mechanism for reclaiming tape as set forth in claim 14, including a take-up spool for the tape having a pulley, a pulley operative by the driving devices, and a belt upon 70 said pulleys adapted to slip when the spool tends to wind tape faster than it is fed by the tape feeding means.

17. Mechanism for reclaiming tape having dissolvable material on its surface comprising a tank for a dissolving solution, rubbing devices for the dissolved material on the tape, rollers to feed the tape, a motor, 75 means operative by the motor to actuate the tape feeding rollers, a circuit for the motor having make and break contacts, and means to actuate the contacts including an arm having means cooperative with the tape to cause the contacts to close or open the motor 80 circuit according to the extent of feed of the tape.

18. Mechanism for reclaiming tape as set forth in claim 17, including a take-up spool for the tape, and means operative by the 85 motor to actuate the spool.

19. Mechanism for reclaiming tape comprising a frame having a plurality of detachable sections, means to detachably retain the sections, a tank for a solution, said frame 90 sections being respectively provided with rollers opposing one another to receive the tape therebetween after entering the solution, gears connected with said rollers to drive one by another, said sections being 95 separable to admit the tape between the rollers, means upon the frame to rotate said rollers against the tape, and a motor to drive 100 said means.

20. Mechanism for reclaiming tape as set forth in claim 19, associated with means to feed the tape to the solution, circuit controlling means for the motor, and means to operate the circuit controlling means cooperative with the tape to control the motor 110 in accordance with the feeding of the tape.

JAMES A. SPENCER.
